TO L C SMITH & CORONA TYPEWRITERS INC., OF SYRACUSE, NEW YORK, A COR-
PORATION OF NEW YORK

TYPEWRITING MACHINE

Application filed August 30, 1929. Serial No. 389,413.

This invention relates to improvements in typewriting machines, and more particularly to paper feeding mechanism for such machines.

The principal objects of the invention are 5 to provide an improved paper bail device for typewriting machines; to provide a simple and durable paper bail mechanism embodying provisions for yieldably pressing the bail against the platen in its "on" position, and 10 for holding the bail in a plurality of "off" positions; to provide a bail and spring-urged controlling means thereof arranged to either yieldably press the bail to the platen, yieldably latch the bail in a full "off" position adjacent the paper shelf, or frictionally hold 15 the bail in any intermediate "off" position upon swinging of the bail about its pivotal axis; and to provide means for either pressing 20 the bail toward the platen or holding the same in various "off" positions, which means consists of few parts of simple and inexpensive construction.

To the above and other ends which will 25 appear from the following description of the preferred embodiment of the invention illustrated in the accompanying drawings, the invention comprises the combinations of devices, features of construction, and arrangements of parts particularly pointed out 30 in the claims.

In the drawings, which illustrate the preferred form of the invention as applied to an L C Smith typewriting machine,

Fig. 1 is a fragmentary top plan view, 35 showing the bail in normal active or "on" position;

Fig. 2 a front view showing the parts of the bail mechanism positioned as in Fig. 1;

Fig. 3 a fragmentary side view, looking 40 from the right hand side of the machine, showing the bail in "on" position;

Fig. 4 a view similar to Fig. 3, showing the bail frictionally held in an intermediate "off" 45 position;

Fig. 5 a side view, looking from the left hand side of the machine, showing the bail yieldably latched in its full "off" position;

Fig. 6 an edge view of one of the pair of 50 bail controlling members; and

Fig. 7 a side view of said controlling member.

The traveling platen carriage comprises side bars 10 and a rear cross-bar 11, and runs on suitable ball bearings 13 in raceways on the stationary framework 12 of the machine. The platen 14 has its shaft 15 journaled in suitable bearings in the side bars 10. The paper is supported and guided to the platen at the rear of the platen by the usual paper shelf 16 mounted on the carriage, and is fed and guided forward under the platen by the usual paper feed devices on the carriage comprising the paper table 17 and feed rollers 18. The type on the heads of the type bars 19 strike on the front portion of the platen, as usual in the L C Smith machine shown, and as indicated in Fig. 3. The improved paper bail mechanism may now be described.

The paper bail comprises a pair of sheet metal side bars or arms 20 and a metal cross-bar in the form of a rod 21, the ends of said rod being rigidly secured by pins 23 in tubular sleeves or bosses 22 rigidly held in the free ends of side arms 20 and extending horizontally inward from the side arms, said bosses having reduced outer portions 24 swaged in holes in the forward ends of the side arms. Instead of having the cross-bar of the bail directly contact the platen, or the paper about the platen, preferably a pair of short feed rollers 32 are provided for contacting the paper, said rollers being journaled on sleeve bearings 33 frictionally held on the cross-bar.

A pair of sheet metal brackets are rigidly secured to the rear cross bar 11 of the carriage for mounting the bail and its controlling devices. These brackets have body portions 25 bent to a right angle between their ends above cross-bar 11, the pendent parts of which lie in a vertical plane extending transversely of the machine and are formed at their lower ends with integral inwardly extending attachment arms 26, each of said arms 26 being fastened by two screws 34 to a pair of bosses 27 on the front face of cross-bar 11, there being a pair of bosses 27 adjacent each end of the cross-bar. The upper sections of the body portions of the brackets

extend rearwardly and lie flatwise in a horizontal plane, the angular body portions of these brackets being located to the rear of and below the upwardly and rearwardly extending paper shelf 16.

The rearwardly extending parts of the brackets have formed integrally therewith at their outer edges, as more clearly shown at 29 in Figs. 1 and 2, bail mechanism supporting arms 28 bent upwardly to lie in parallel vertical planes extending fore and aft of the machine, said supporting arms and pendant extensions 30 thereof preferably abutting outer edge portions of the horizontal and vertical parts of the main angular bodies 25 of the brackets, as shown, to stiffen the bail mechanism supporting structure.

The rear ends of the side arms 20 of the bail lie against the outer faces of supporting arms 28 of the brackets at the forward ends of said arms 28 and are pivotally held to arms 28 at these points by shouldered pivot screws 31 for swinging of the bail upwardly and rearwardly about an axis parallel with the axis of the platen and located slightly above and to the rear of the platen, from an "on" or active position in which the feed rolls 32 contact the platen, or paper thereabout, at points on the upper front portion 30 of the platen in a line clear of the type bar heads in printing position, to a full "off" position in which the cross-bar and rolls lie close to the front face of the upper end of the paper shelf 16 but spaced from the shelf sufficiently for free passage therebetween of both the leading and following portions of a plurality of superposed work sheets in the machine.

The paper bail is adapted to be swung 40 about its pivotal axis by the operator grasping the same with the fingers, and is held on or off, dependent upon the position to which it is so moved, automatically by a pair of spring urged pivoted controllers mounted 45 on the pair of sheet metal brackets 25. Each controller comprises a flat sheet metal swinging arm 35 extending fore and aft and disposed flatwise in a vertical plane located slightly outside the plane of the adjacent arm 28 of the bracket 25 to which it is pivoted. Arms 35 are each provided with an inwardly extending sleeve bearing or hub 36, the outer end of which is swaged in an opening in the rear end of the arm, and a shouldered pivot screw 37 extends inwardly through the hub and is threaded through the adjacent bracket arm 28 with the inner end of the controller arm hub abutting the outer face of bracket arm 28. Screws 37 pass through arms 28 at a point slightly above the level of the rearwardly extending parts of brackets 25 and the pivotal axis of the bail, and about mid-length of arms 28, and lock nuts 38 are preferably screwed on the inner

ends of the screws against the inner faces of the bracket arms 28.

The free end of each controller arm 35 is normally urged downward by a wire spring 39 coiled around the controller arm hub and having its opposite ends anchored to headed 70 studs 40 and 41 on the controller arm and the adjacent bracket arm 28. Stud 40 projects inward from the controller arm at a point above the pivot of said arm, and stud 41 projects outwardly from bracket arm 28 at a point below and to the rear of the controller arm pivot, spring 39 being wound about the hub in a direction to exert a constant yielding pressure on the controller arm urging the arm 80 downward.

Side arms 20 of the bail carry outwardly projecting studs 42, preferably having metallic anti-friction rollers 43 journaled thereon, the stud 42 on each side arm being located a short distance from the bail axis and between said axis and the bail cross-bar. The controller arms are provided with identical longitudinal cam slots 44 through which said studs 42 with their rollers 43 project. Slots 44 are arcuate slots each having a relatively long intermediate dwell edge portion 45 and two short camming edge portions 46 and 47 at opposite ends of the slot along the top wall of the slot, said slot being somewhat wider than the diameter of the roller engaged therein so that the roller will not contact the bottom wall of the slot while the top wall of the slot is held constantly pressed against the roller by spring 39.

Dwell edge portions 45, when engaged by the rollers on the bail side arms, extend in an arc corresponding with the path of swinging movement of the rollers with the bail, i. e. in an arc struck from the pivotal axis of the bail as a center. Camming edge portions 46 and 47 are eccentric to the bail axis in all positions of the bail, curving from opposite ends of the dwell edge portion toward the upper edge of the arm and being located, respectively, forward and rearward of the vertical plane of the bail axis.

It will be obvious from the foregoing description, that when the bail is swung rearward until the rollers engage cam edge portions 47 of the controllers, the bail will be cammed rearward by the controllers until the rollers engage the rear ends of slots 44 and then arrested, as shown in Fig. 5, the length of the slots being such that the rearward swinging of the bail is arrested by the controllers with the cross-bar and feed rollers 32 slightly forward of the upper end of the paper shelf 16. It will also be observed that the controllers, in this full "off" position of the bail, act as spring latches to yieldably latch the bail in said position so as to require upward swinging of the controllers against the resistance of the springs 39 to dislodge the bail from said position. Cam por-

tion 47 is preferably made quite short, as shown, so as to be only long enough for cam portion to hook securely over the roller with the roller contacting the rear end of the slot.

5 When the rollers are engaged with the long dwell portions 45 at any point along said portions, the spring pressure is exerted on the bail in a radial plane passing through the rollers 43 and the pivotal axis of the bail, so 10 that the springs 39 and the controllers rocked thereby cannot exert a bail swinging thrust on the bail, and so that the pressure on the rollers will enable the controllers to frictionally hold the bail in whatever intermediate "off" 15 position it may be moved to, for example the position shown in Fig. 4.

When the bail is swung forward and downward from "off" position until the rollers engage cam portions 46, the controllers will cam 20 the bail forward and downward until the feed rollers 32 on the bail cross-bar contact the platen, or the paper passing upwardly there-over, and will yieldably hold the rollers 32 in "on" position. Slots 44 are of such length 25 that rollers 32 contact the platen before rollers 43 on the bail side arms can reach the forward ends of the slots. Cam portions 46 are sufficiently long to permit rollers 43 to ride slightly back and forth therealong to 30 permit the bail to yield to compensate for varying numbers and thicknesses of paper sheets and inequalities in the paper sheets or platen surface without throwing the bail side arm rollers on to the dwell portions 45 of the 35 controller cam slots. It will thus be observed that the controllers act as yielding latches to yieldably hold the bail in "on" or active position.

What we claim is:

40 1. In a front strike typewriting machine, the combination of a paper carriage, a platen on the carriage, a paper bail having rearwardly extending side arms pivotally held to the carriage for swinging of the bail about an axis in rear of the vertical plane of the platen, a pair of fore and aft extending controller arms pivotally held at their rear ends to the carriage to swing about an axis parallel with the bail axis, a pair of springs connected with the carriage and said arms to urge the arms downwardly, said arms each having a cam edge having two active portions and an intermediate dwell portion, and laterally projecting means carried by the bail 45 side arms and engaged under the cam edges of said controller arms, the two active portions of each cam edge being arranged to swing the bail in opposite directions, and the dwell portions of the cam edges being curved 50 so as to lie in an arc conforming with the path of movement of the laterally projecting means when engaged therewith.

55 2. In a front strike typewriting machine having a paper carriage, a platen journaled on the carriage, and a paper shelf extending

upward and rearward from behind the platen, the combination of a paper bail having a cross-bar overlying the platen in the "on" position of the bail and side arms extending rearwardly from said cross-bar and pivotally held to the carriage above and to the rear of the platen, a pair of fore and aft extending controller arms pivotally held to the carriage in rear of the bail axis at their rear ends to rock up and down, springs connected with the carriage and controller arms for rocking the arms downward, said arms having longitudinal slots, the top edges of which have cam portions at their ends and an intermediate dwell portion, and means projecting laterally from said bail side arms between their pivots and the cross-bar and rockable with said arms and engaged under the top edges of the slots, the cam edge portions at the forward ends of the slots being disposed to thrust said laterally projecting means toward the platen while the cam edge portions at the rear ends of the slots are adapted to thrust said means away from the platen against the rear end walls of the slots to 90 a position in which the bail cross-bar lies spaced slightly forward of the upper end of the paper shelf.

3. In a typewriting machine, the combination of a carriage, a platen on the carriage, a paper bail pivotally held to the carriage, and a pivoted pressure member on the carriage constantly urged in one direction and constantly bearing against a part of the bail, to exert pressure on said part in a straight line passing through the bail axis and the point of contact throughout a part of the throw of the bail to variably hold the bail cross-bar out of paper controlling relation with the platen, and to exert pressure on said part in a direction to carry the bail cross-bar into and yieldably maintain it in paper controlling relation with the platen, said member having a portion arranged for engagement by said part of the bail to positively limit 105 swinging movement of the bail in the direction carrying the bail cross-bar away from the platen.

4. In a typewriting machine, the combination of a paper carriage, a rotatable platen on the carriage, a paper holding bail having side arms pivotally held to the carriage to swing about a fixed axis parallel with the platen axis, an arm for controlling swinging of the bail about said axis between an extreme inactive position and paper holding position, said arm being pivotally held to the carriage to swing about a fixed axis different from but parallel with the bail axis, a spring constantly urging said arm in one and the same direction around its axis in all positions of the bail, one side arm of said bail being provided with a lateral projection, and said bail controlling arm having a contact surface along which said projection travels 115 120 125 130 135

during swinging movements of the bail, said contact surface comprising an intermediate arcuate portion which exerts pressure on said projection in a line passing through the bail

- 5 axis throughout a substantial intermediate portion of the bail throw to hold the bail in variable intermediate inactive positions, and two terminal portions connected by said arcuate portion, one of which terminal portions exerts pressure on said projection in a direction to urge the bail to the platen throughout one end portion of the bail throw, and the other of which terminal portions exerts pressure on said projection in a direction to urge the bail away from the platen throughout the opposite end portion of the bail throw.

10 5. In a typewriting machine, the combination of a platen carriage, a rotatable platen 20 on the carriage, a paper holding bail coactive with the platen to hold paper thereto and having side arms pivotally held to the carriage to swing about a fixed axis parallel with the platen axis for movement of the bail out 25 of active position, a spring urged controller arm pivotally held to the carriage to swing about a fixed axis parallel with the bail axis and constantly spring urged in one and the same direction about its axis, said controller arm having a cam edge constantly pressing on the bail at a fixed point on the bail and comprising a dwell portion for exerting thrust on the bail in a line passing through the bail axis and an active portion at one 30 end of said dwell portion for exerting thrust on the bail in a line passing to one side of the bail axis and in a direction to urge the bail to the platen.

- 35 6. In a typewriting machine, the combination of a platen carriage, a rotatable platen on the carriage, a paper holding bail having side arms pivotally held to the carriage to swing about a fixed axis into and out of paper holding relation with the platen, a bail controlling arm pivotally held to the platen carriage to swing about a fixed axis different from but parallel with the bail axis and having a direct pin and slot connection at one 40 side of its pivotal axis with one side arm of the bail, and a spring constantly urging said controlling arm in one and the same direction around its axis, said slot having a longitudinal cam edge with two active end portions connected by a dwell portion, one of 45 which end portions is coactive with said pin to swing the bail toward the platen and the other of which is coactive with said pin to swing the bail away from the platen until the 50 pin is engaged with the adjacent end of the slot, said dwell portion and pin being coactive throughout a substantial portion of the swinging throw of the bail to transmit pressure from said spring to the bail constantly 55 in a line passing through the bail axis and the

point of contact of the pin with the dwell edge portion.

In testimony whereof we hereunto affix our signatures.

CARL GABRIELSON.
CHARLES WAUCQUEZ.
